FOG NOZZLE

Thomas R. Day, Buffalo, N. Y.

Application August 24, 1936, Serial No. 97,587

7 Claims. (Cl. 299—124)

This invention relates to spraying nozzles, and particularly to those which may be advantageously employed for the creation of water fog. Water fog is being used to an increasing extent in the fighting of fires, particularly oil and gasoline fires. Water fog has been found to be particularly effective in fighting fires, because the blanket of fine water spray discharged around the burning material is more effective in many cases in subduing the fire than would be the discharge of substantial streams of water against the same burning material. It is well recognized that when a given body of water in the form of a solid stream, is broken up into a plurality of small particles, the effective or total surface of the water in contact with the fire or heat is increased, that is, the surface area of the water exposed to the fire is increased. When water in this extremely fine fog form comes in contact with the fire, it is changed into steam and its volume is multiplied 1700 times, since the steam represents approximately 1700 times the volume of water applied.

It is apparent, therefore, that through the process of breaking up and being transformed into steam, the heat absorbing and cooling qualities of a given volume of water are increased to the maximum possible extent. The water discharged in such fine form extinguishes the fire by absorbing the heat of the fire and at the same time cooling the combustible material below the kindling point, and in the process of absorbing heat, steam is generated in the space between the fire and the burning material, thereby excluding oxygen, so that there is also a smothering action at the same time. The water in this form does not disturb the surface of any burning substance, such as oil for example, as does a solid stream of water or other fluids.

In order to break up the water into a fine spray, it is necessary to discharge the stream of water through one or more restricted passages or orifices, and if these orifices or passages should become clogged or plugged through the lodging therein of foreign matter, the effectiveness of the nozzle as a spraying device may be greatly decreased or its effectiveness entirely lost, and hence it is important that some provision be made for cleaning any plugged spray-creating passages or orifices without shutting off the water to the nozzle for the cleaning operation. It is also desirable that the same nozzle be capable of throwing a stream in the form of a fog, or as a stream of more or less solidarity, so that whenever conditions require the use of a water fog, the nozzle

may be set to create the fog, and when a substantial stream of water is desired, the nozzle may be set to discharge such a stream.

One object of this invention is to provide an improved and simplified nozzle with which a water fog may be created, and which if plugged with foreign matter may be easily and quickly cleaned without shutting off the supply of water to the nozzle, and which will be relatively simple, compact, durable, efficient and inexpensive.

Another object of the invention is to provide an improved spraying nozzle which may be set selectively to discharge a stream of substantial body or to discharge a water fog of different degrees of fineness, with which the adjustment for the type of stream desired may be quickly and easily made while the discharge of water continues, and which may be manipulated and adjusted to deliver the water in the desired form or condition while in use by a single operator.

Another object of the invention is to provide an improved and more efficient spraying nozzle for creating a water fog, with which the danger of blocking or plugging is decreased, and which may be quickly and easily cleaned of foreign matter while in operation.

Various other objects and advantages will be apparent from the following description of two embodiments of the invention, and the novel features will be particularly pointed out hereinafter in connection with the appended claims.

In the accompanying drawing:

Fig. 1 is a side elevation of a spraying nozzle constructed in accordance with this invention and illustrating one embodiment thereof;

Fig. 2 is a longitudinal sectional elevation of the same;

Fig. 3 is a plan of the same; and

Fig. 4 is a longitudinal, sectional elevation through a nozzle constructed in accordance with this invention and illustrating a modification thereof.

In the embodiment of the invention illustrated in Figs. 1 to 3, the improved device includes a nozzle body 10 having a passage 11 therethrough from end to end. The passage 11 may have a progressively constricted zone or portion 12, as common in nozzles, in order to increase the velocity of the stream moving in the passage toward the outlet end. The body 10 may be provided with screw threads 13 in the larger end of the passage 11 so as to permit coupling of the nozzle to a pipe or hose shown in dash lines in Fig. 1 through which water to be discharged is obtained. The hose or pipe is of course then con-

nected to a fire hydrant or other source of water or liquid under pressure.

The passage 11 at its smaller or discharge end is provided with an annular groove 14 opening 5 into the passage and the end face of the body, so as to form a shoulder 15 that serves as a seat for a valve element 16. In this embodiment of the invention, the valve element is in the form of a sphere or ball which has a diameter somewhat greater than the diameter of the passage 10 11 at the seat 15, so that when the ball 16 abuts the seat 15, a portion of the surface of the sphere, which may be considered as a tapering zone, will project through the seat into the passage 11 and 15 act as a guide for directing the ball or sphere 16 into seating position. The outer wall of the groove 14 extends toward and faces the surface of the ball, and when the ball is resting on the seat 15 there is only a very slight clearance between the periphery of the ball and the outer 20 wall of the groove 14.

Suitable means is provided for limiting the displacement of the valve element, i. e., the ball or sphere 16, outwardly from the seat 15, and this 25 means is preferably adjustable from outside of the stream of liquid discharged through the space between the ball periphery and the seat 15. A simple and preferred form of such a confining means comprises a ring 17 which is threaded upon 30 the periphery of the body 10, such as adjacent the discharge end thereof, so that when the ring 17 is turned it will be threaded endwise along the nozzle in one direction or another, dependent upon the direction of turning. Arcuate cage elements 35 or wires 18 extend from opposite sides of the ring 17 across the discharge end of the passage 11 of said body, so as to form cage which confines the valve element such as the ball or sphere 16 to the discharge end of the nozzle, and limits its possible 40 displacement away from the seat 15 to an extent determined by the threaded adjustment of the ring 17 along the nozzle body.

Thus by turning the ring 17 in one direction the ball or sphere 16 may be forced against the 45 outwardly facing seat 15 so as to shut off or stop the discharge of all liquid from the nozzle. By turning the ring 17 in the other direction the ball or sphere 16 is released and increasing 50 displacement of the same away from the seat permits the discharge therethrough of a tubular, diverging stream of liquid having a wall thickness depending upon the extent of displacement of the ball or sphere 16 from the seat 15. When the ball or sphere 16 is only slightly displaced 55 from the seat the amount of liquid discharged is of course small, and the hollow stream of liquid as discharged has a wall thickness equal to the distance from the seat 15 to the surface of the sphere or ball. As a result, this thin walled, 60 diverging, hollow stream of liquid is broken up into a fine spray, and this action is increased by reason of the fact that the outer wall of the groove 14 acts as a deflector to the outwardly spreading stream, to divert or deflect a substantial portion of it against the face of the ball, thereby forming a very fine, mist-like spray.

The breaking up of the liquid into the fine spray is also increased to some extent by the provision of a plurality of peripherally extending 70 grooves 19 in the wall of the passage 11 immediately in front of the seat 15, the grooves preferably having abrupt shoulders facing the moving stream. Such shoulders increase the formation of eddy currents in the peripheral zone of the stream moving along the passage, 75

and thus increase the tendency of the tubular stream leaving the nozzle to disintegrate into fine particles. The periphery of the ring 17 may be provided with knurling 20 to facilitate the threading of the ring along the nozzle body. 5 By threading the ring further towards the discharge end, and allowing considerable displacement of the ball or sphere from the seat 15, a diverging stream of considerable volume can be provided when occasion for a considerable volume of water in the stream is present.

Any foreign matter that may have collected in the small annular space between the seat 15 and the surface of the ball or sphere when the nozzle is being used as a fog creating device, is 15 immediately carried away and discharged when the ring 17 is moved so as to permit a considerable displacement of the ball or sphere from its seat. Thus if the nozzle, when set to create a 20 fog, becomes plugged or stopped by foreign matter to any extent, it may be manipulated to clear such foreign matter merely by first turning the ring 17 to increase the maximum possible displacement of the sphere from its seat while the nozzle is in use, and then again turning the ring 25 to draw the ball or sphere back into its desired spray-creating position with respect to its seat 15.

The embodiment shown in Fig. 4 is similar to that shown in Figs. 1 to 3 except that the valve 30 element 21 instead of having the form of a ball or sphere is provided with a conical surface which seats against the seat 15 in the same manner that the ball 16 engaged with seat 15, with the tapering end of the cone projecting into 35 the passage of the nozzle. This element 21 has its conical surface extending in both directions along the passage from the seat to a substantial extent, and the character of its upper surface is immaterial, although for convenience it is shown 40 as a portion of a sphere in order to accommodate itself readily to the arcuate wires forming the cage that confines it to the nozzle body. In this embodiment of the invention, the grooves 19 of the passage have been omitted, although it will 45 be understood that they may be provided as in Figs. 1 to 3 if desired.

The operation and use of the improved nozzle have been explained as the description has proceeded, and are believed to be clear. It will be 50 noted that the nozzle may be easily and quickly adjusted to vary the character and form of the stream discharged while in use, and the stream may be cut off entirely if desired, so that the improved device functions as a cut off valve as well 55 as an adjustable spray creating device that may be set to throw a stream of considerable size and body whenever desired. Any plugging or stoppage of the nozzle by foreign matter while being used as a fog-creating device may be 60 quickly and easily remedied and the nozzle cleared of such foreign matter, merely by turning ring 17 to open the nozzle and increase the flow of water therethrough and then decreasing it to a spray creating condition. Thus, I have a 65 nozzle which possesses all the advantages of a fog creating nozzle, and also of the ordinary nozzle for throwing a stream of considerable volume or size, as conditions may require or make advisable, and with this improved device 70 any substitution of nozzles on the end of the hose or pipe becomes unnecessary.

Fog nozzles made in accordance with this invention have the further advantages that when 75 adjusted to produce a fine spray or fog, this fog

forms a curtain or screen between the fireman and the fire which protects the fireman not only from the heat of the fire but also from the smoke. The protection from the heat is, of course, due to the fact that the finely divided water particles readily become vaporized and thus absorb the heat, and protection from smoke is probably due both to the dissolving of smoke in the finely divided water particles and to the blowing away of the smoke by the spray of fog. It has, consequently, been found that with the use of these nozzles, firemen can approach into very close proximity to fires without danger of being overcome or even inconvenienced by smoke or heat, and the use of gas masks in the case of smoky fires is, consequently unnecessary in most cases when my improved fog nozzles are used. Consequently, by using the spray of fog as a screen, a fireman can also enter into a burning building with greatly reduced danger of being overcome by smoke. My improved fog nozzles have also been found very effective in extinguishing grass fires by means of fog.

The fog from the nozzles can also be used to excellent advantage in confined or partly confined fires in that such fires can be readily smothered by the fog and steam resulting therefrom. When fires in buildings are extinguished by means of fog, the damage due to water is very materially reduced, and sometimes entirely avoided.

It will be understood that various changes in the details and arrangements of parts, which have been herein described and illustrated in order to explain the nature of the invention, may be made by those skilled in the art within the principle and scope of the invention as expressed in the appended claims.

I claim:

1. A spraying nozzle comprising a body having a passage therethrough, with an outwardly facing seat adjacent the discharge end of said passage, a spray creating element abutting said seat from the outer end of the passage and having a portion on each side of the seat engaging zone progressively decreasing in transverse dimensions, means carried by said body for confining said element to the end of said passage in close proximity to said seat, the wall of said passage outwardly from said seat having an annular shoulder of larger diameter than said seat and facing said element for diverting a portion of a liquid stream escaping from said passage through the space between said seat and said element, against the peripheral face of said element to increase the break up of the stream into small particles.

2. A spraying nozzle comprising a body having a passage therethrough with an outwardly facing seat adjacent the discharge end of said passage, a spray creating element at said end, abutting said seat, and having a tapering portion extending into said passage from said seat and a diverging portion extending outwardly from said seat, and means carried by said body and engageable with said element for limiting the maximum outward movement of said element when a stream of liquid is discharged from said passage outwardly through said seat, said passage having an annular groove therein outwardly from said seat and facing said element, but with a slight clearance from said element when said element is in engagement with said seat, whereby when the maximum possible clearance between the periphery of said element and its seat is small, the escaping, hollow, diverging stream will be deflected to

some extent by said groove against the diverging surface of said element and will be broken up into a fine spray.

3. A spraying nozzle comprising a body having a passage therethrough with an outwardly facing seat adjacent the discharge end of said passage, a spray creating element at said end, abutting said seat, and having a tapering portion extending into said passage from said seat and a diverging portion extending outwardly from said seat, and means carried by said body and engageable with said element for limiting the maximum outward movement of said element when a stream of liquid is discharged from said passage outwardly through said seat, the wall of said passage just in advance of said seat having an annular groove formed with abrupt edges to cause eddy currents in the stream impinging on said diverging portion of said element as it is discharged.

4. A spraying nozzle comprising a body having a passage therethrough with an outwardly facing seat at the discharge end of said passage surrounded by an annular groove of larger diameter, a ring threaded to the periphery of said body for adjustment in directions endwise of the body, a cage element carried by said ring and extending across the discharge end of said passage, a closure element confined in the discharge end of said passage by said cage element and having a tapered peripheral surface engageable with said seat for controlling the liquid discharge from said passage, the adjustment of said ring obtained by threading it along said body forcing said cage element along said body in order to shut off all flow, or to release said cage element for increasing possible displacement outwardly of said passage, depending upon the direction of turning of said ring.

5. A spraying nozzle comprising a body having a passage therethrough from end to end, and having a shallow, radially and outwardly opening, annular groove with abrupt shoulders and forming a slight enlargement of said passage at its discharge end, an element disposed against the end of said body at said discharge end of the passage and engageable with the seat formed at the smaller periphery of said groove, a ring mounted on the periphery of said body for adjustment thereon in directions endwise of said body, and a cage element carried by said ring and extending across the discharge end of said passage for confining said element to the discharge end of said passage and limiting its maximum possible displacement away from said seat.

6. A spraying nozzle comprising a body having a passage therethrough from end to end, with an outwardly facing seat at approximately the discharge end of said passage, an inwardly tapering element disposed in said discharge end and seating against said seat, the end of said passage outwardly from said seat having a sharp, annular shoulder facing said element for diverting against the periphery of said element a portion of any liquid stream passing through said seat and between it and said element and thereby creating cross currents in the emerging stream acting to break said stream into mist or fog, and means for limiting the maximum possible displacement of said element outwardly away from said seat.

7. A nozzle for transforming a stream of liquid into a fog-like spray which comprises a body having a passage therethrough and through which the liquid is discharged under pressure differential, said passage having an outwardly facing, an-

nular groove approximately at its discharge end, the inner side wall of said groove forming an annular valve seat, a spray creating element movable against said seat from the discharge end of said passage, having a converging portion extending past said seat into said passage in a counterflow direction, and having a diverging portion extending outwardly from said seat in the direction of flow, the outer wall of said groove ex-

tending towards and into close proximity to said element for increasing the break up of the discharged stream, and means engaging said element for limiting the movement of said element outwardly away from said seat and adjustable to vary the extent of such outward movement of said element. 5
